KARL A. BRAUNING, OF STAMFORD, CONNECTICUT, ASSIGNOR TO THE YALE & TOWNE MANUFACTURING COMPANY, OF STAMFORD, CONNECTICUT

PLUG RETAINER

Application filed May 4, 1929. Serial No. 360,485.

This invention relates to cylinder locks, more especially to means for securing the plug of a cylinder lock within the cylinder. It has been customary in securing a plug within its cylinder, to screw a retaining cap on to the end of the plug, this retaining member or cap acting to maintain the plug within the cylinder. The purpose of this invention is to substitute for this cap a sliding spring member which may be inserted in a slot in a plug extension for maintaining the plug within the cylinder. This method obviates the former danger incident to the loosening of the screws and furnishes a readily releasable means for removing the plug when desired.

For a more detailed description of my invention, I refer to the drawing wherein Fig. 1 is an elevation of my cylinder showing a connecting bar attached thereto. Fig. 2 is an end view of the same. Fig. 3 is a view of my spring slide retaining member. Fig. 4 is a view of the connecting bar. Fig. 5 is a view of the plug showing the dovetail slot for the retention of the spring retaining member. Fig. 6 is a section through the plug showing my retaining member in position and the connecting bar in its relationship to the plug. Fig. 7 is an enlarged view of the end of the plug in Fig. 2.

Referring more particularly to the drawing, reference numeral 10 designates a cylinder adapted for the usual type of plug 11 which in turn is equipped with a dove-tail slot 12 as shown in Fig. 5. A connecting bar 13 is adapted to fit into the deep portion 14 of the slot 12 for operation by the plug and is secured there in a manner to be described presently. The plug 11 has an extending portion 15 extending beyond the rear wall 16 of the cylinder and as shown, the horizontal portion 17 of the dove-tail slot 12 is adapted to assume a position in juxtaposition to said cylinder wall 16 for a purpose hereinafter explained.

A spring retainer slide 18 is shown in Fig. 3. This retainer slide is slotted at 19' to form two spring arms 19 and 20 which are adapted to be spring-pressed together whenever desired, so that they may enter the horizontal

portion 17 of the dove-tail slot 12. Once these spring arms are allowed to go beyond the slot, they will spring outwardly, as shown in Figs. 6 and 7, and the retainer 18 will rest against the end wall 16 of the cylinder to retain the plug therein. In addition to its function as a means for supplying the necessary spring action, the retainer slot 19' is utilized to maintain the connecting bar 13 in position. The lugs 20' of this connecting bar lie in the deep portion 14 of the dove-tail slot 12 and since they are adapted to extend beyond the slot 19', the retainer 18 will be able to hold the bar 13 within the plug in the manner shown.

I claim:

1. In a cylinder lock, a plug extending beyond the rear cylinder wall, an internal diametric dove tailed slot in said plug extension, and a spring retainer slide adapted to fit in said slot and to be contained entirely within the plug except at its ends which cooperate with the cylinder to maintain the plug in the cylinder.

2. In a cylinder lock, a plug having its rear end extending beyond the cylinder, an internal diametric slot in said extension in juxtaposition to the rear cylinder wall, and a slide adapted to enter said slot and having its diametric opposite ends extending beyond the slot to maintain said plug in the cylinder by cooperation with said cylinder wall.

3. In a cylinder lock, a key plug extending beyond the rear cylinder wall, an internal diametric slot in said extending portion in juxtaposition to said cylinder wall, and a slotted retaining member having spring arms pressing outwardly against the walls of the slot and adapted to be removably inserted in said slot to retain the plug in said cylinder.

4. In a cylinder lock, a plug extending beyond the rear cylinder wall, a slot in said extending portion, a slide having one end thereof enlarged and the other end comprising spring arms, said slide being adapted to rest in said slot and have its ends extend outside the slot and against said rear cylinder wall to retain the plug within the cylinder.

5. In a cylinder lock, a plug extending beyond the rear cylinder wall, a slot in said ex-

tending portion, a connecting bar, and releasable spring means adapted to carry said connecting bar and then to enter said slot with said connecting bar to retain the plug in the cylinder and operatively attach said bar to the plug.

6. In a cylinder lock, a plug carried by said cylinder, a slot in said plug, a connecting bar, and a slide adapted to carry said bar and to enter said plug slot.

7. In a cylinder lock, a plug having its rear end extending beyond the cylinder, a slot in said extension, a connecting bar, and a slide adapted to carry said connecting bar and to be maintained in said plug slot.

8. In a cylinder lock, a plug having one end extending beyond the rear end of the cylinder, a slot in said extension in juxtaposition to the end of said cylinder, a connecting bar, a slide adapted to carry said connecting bar and to be maintained in said plug slot to retain the plug in said cylinder.

9. In a cylinder lock, a key plug extending beyond the rear cylinder wall, a dove tailed slot in said plug, a connecting bar having a headed end resting in a portion of said slot, a perforated slide having spring arms and adapted to be sprung pressed into said slot to maintain the plug in the cylinder, said slide having its perforated portion cooperable with said connecting bar and said headed portion to maintain the connecting bar in said plug.

Signed at Stamford in the county of Fairfield and State of Connecticut this first day of May A. D. 1929.

KARL A. BRAUNING.
